UNITED STATES PATENT OFFICE.

RICHARD L. CUSHING, OF TISKILWA, ILLINOIS.

EXPLOSIVE SHELL.

1,306,215.

Specification of Letters Patent. Patented June 10, 1919.

Application filed June 11, 1918. Serial No. 239,452.

To all whom it may concern:

Be it known that I, RICHARD L. CUSHING, a citizen of the United States of America, residing at Tiskilwa, in the county of Bureau and State of Illinois, have invented new and useful Improvements in Explosive Shells, of which the following is a specification.

The invention relates to explosive shells and seeks to provide as its principal object, a device of this kind comprising several compartments, one of which is designed to carry shrapnel, another powder and still another gasolene, certain other compartments carrying units made up of double containers which carry gasolene and powder, the two latter being separate from each other.

A further object is to provide a shell of this kind having a time fuse to ignite the powder in one compartment thereby exploding the shell and distributing the shrapnel and the gasolene, there being means for igniting the gasolene, so that its flames may be distributed over the object at which the shell is fired, such as airships and the like.

A still further object is to provide a shell of this character which is simple in construction and yet durable and effective in operation.

Still further and other objects will be made apparent in the following detail description.

To the exact construction in which it is shown and described, the invention is not to be restricted. The right is reserved to make such changes or alterations as the actual reduction to practice may demand, in so far as such changes or alterations may be compatible with the spirit by the annexed claims.

In the accompanying drawings:

Figure 1 is a longitudinal sectional view of the improved shell,

Fig. 2 is a transverse sectional view,

Fig. 3 is a section on the line 3-3 of Fig. 1.

Referring to the drawings, the shell is shown as comprising a cylindrical shell 1 on one end of which the nose 2 is formed. The nose is hollow and carries therein the shrapnel 3, which is inclosed within the nose by means of a plate 4, the periphery of the plate frictionally engaging the inner wall of the nose at its line of juncture with the shell proper. A longitudinal tubular

member 5 is disposed centrally in the shell 1 and extends for the greater part of the length of the shell. In surrounding relation to this tubular member 5, there is a second tubular member 6 which is concentric with the member 5. A plate 7 serves to close one end of each of the tubular members 5 and 6, the opposite ends being formed with permanent closures.

The tubular members 5 and 6 extend in spaced relation to each other, and the latter stands in spaced relation to the walls of the shell 1.

Standing in spaced relation to the plate 7, there is a further plate 8 whose periphery frictionally engages the inner walls of the tubular member 1.

The rear end of the casing 1 is closed by a plate 9 which is provided with a hole 10 and with a circular trench 11, one end of which terminates in the hole. This hole 10 is designed to hold some quick acting powder and the trench 11 is intended to be supplied with a fulminate. Connecting with the rear end of the shell 1 by threading engagement with the latter, there is a second plate 12 provided with a hole 13 having a radial distance from the center of the plate equal to the radius on which the trench 11 is formed, the trench being concentrically disposed on the plate 9. The plates 12 and 9 together operate to form a time fuse, the angular adjustment of the plate 12, to move its hole 17 toward and away from the hole 10 determining the interval of time necessary for the operation of the fuse.

The space in the shell 1 comprehended between the plates 8 and 9 is designed to receive the powder charge 14. The tubular member 5 incloses the powder charge 15 and the tubular member 6 incloses gasolene. A fuse 16 connects the charge of powder 14 with the charge 15.

All the space comprehended between the tubular member 6 and the shell is designed to receive the hand grenades 16', each of which comprises an outer container 17 and an inner container 18, both of which have the common top 19 with the container 18 supported within the container 17 by the said top 19. This top or cover 19 is fixed to both containers 17 and 18 in any suitable manner and carries an eye 20. The containers are arranged in sets, the several comprising any one set being interconnected by

means of a chain member 21. Fuses 22 connect with the powder charge 14 and one fuse leads to each of the several sets of the containers of the grenades 16, the fuse communicating with the interior of the containers 18 in each of which a powder charge 23 is carried.

Each of the containers 17 carries a supply of gasolene.

10 The plate 8 is intended to be held in place frictionally in the shell 1, but the latter is provided with an abutment flange 24 to keep the plate when being inserted from moving further than a prescribed distance into the shell. The grenades 16 are secured in place and held against movement in the shell by means of rosin or some other suitable substance 25 which is poured in at the time the shell is being made and occupies all the 15 space exterior to the tubular member 6 and between the plates 7 and 8 except such space as is occupied by the grenades and their attendant equipment.

In the operation of the device, the time 25 fuse previously referred to is adjusted so as to operate after the lapse of the desired interval of time. The shell is then fired and, after the powder charge 14 explodes, the shell or casing 1 is blown to pieces, the powder charge 14 tending to force the entire 30 contents of the shell forwardly. The explosion of the shell serves to distribute the shrapnel 3 in all directions, thus effecting the desired damage to the object at which 35 the shell was aimed. The exploding of the shell also serves to throw the gasolene in the tubular member 6 in all directions, the powder igniting the gasolene when the latter is exposed to the air, thereby spreading a volume 40 of flame from the exploding shell. Each set or battery of grenades 16 is also thrown out with the explosion of the shell, the fuses 22 serving to ignite the powder charges 23 in the containers 18 of the latter, thus 45 igniting the gasolene in the containers 17.

It will be seen that the shell thus becomes very effective against air craft by providing means for setting the latter on fire as well as providing means for damaging the same 50 by the exploding shrapnel.

The foregoing description taken in conjunction with the drawings makes the construction and operation of the invention

readily apparent and further description, is therefore, unnecessary.

The invention having been described what is claimed as new and useful is:

1. In a device of the kind set forth, a cylindrical shell, a nose secured to one end of the shell, the nose being hollow and being 60 designed to contain shrapnel, a plate secured against the end of the shell and holding the shrapnel within the nose, a tubular member interior to the shell, a second tubular member in surrounding relation to said tubular member, a second plate secured within the shell and closing the two aforesaid tubular members, a third plate held within the shell and spaced from the second plate, a time 65 fuse device closing the shell at the rear end, 70 and a plurality of grenades carried within the shell and between it and the aforesaid second tubular member, the second said tubular member being designed to contain gasolene, the shell itself being designed to contain 75 powder in the space between the last said plate and the time fuse device.

2. In a device of the kind set forth, a cylindrical shell, a nose secured to one end of the shell, the nose being hollow and being 80 designed to contain shrapnel, a plate secured against the end of the shell and holding the shrapnel within the nose, a tubular member interior to the shell, a second tubular member in surrounding relation to said 85 tubular member, a second plate secured within the shell and closing the two aforesaid tubular members, a third plate held within the shell and spaced from the second plate, a time fuse device closing the shell at 90 the rear end, and a plurality of sets of interconnected grenades in the space between the second tubular member and the shell, the first said tubular member being designed 95 to contain a charge of powder, the second tubular member being designed to contain gasolene, the shell itself being designed to contain powder in the space between the last said plate and the time fuse device, a fuse connecting the powder charge in the shell 100 with that in the first said tubular member, and fuses connecting the powder charge in the shell with each set of grenades.

In testimony whereof I affix my signature.

RICHARD L. CUSHING.
